CLAIM

The ornamental design for a video camera system, as shown and described.

DESCRIPTION

FIG. 1 is a top, front and right side perspective view of a video camera system showing our new design;

FIG. 2 is a top, front and left side perspective view thereof, shown with the camera lens tilted towards the right side;

FIG. 3 is a bottom, front and left side perspective view thereof, shown with the camera lens tilted towards the left side;

FIG. 4 is front plan view thereof;

FIG. 5 is a back plan view thereof;

FIG. 6 is a top plan view thereof;

FIG. 7 is a bottom plan view thereof;

FIG. 8 is a left side plan view thereof; and,

FIG. 9 is a right side plan view thereof.

The broken lines depict portions of the video camera system in which the design is embodied that form no part of the claimed design.
